UNITED STATES PATENT OFFICE.

GEORGE H. BENT, OF BATTLE CREEK, MICHIGAN.

DELIVERY MECHANISM FOR CARTON SEALING MACHINES.

Application filed May 21, 1924. Serial No. 714,976.

This invention relates to carton sealing machines and more particularly to delivery mechanism for the same.

The principal objects of this invention are 5 to provide mechanism which grips sealed and filled cartons fed thereto by the conveyor of a sealing machine and transfers the cartons to an offset delivery conveyor; which successively grips, transfers and releases the filled cartons for deposit onto the offset delivery conveyor; which preferably ejects the released filled cartons from the transferring devices to insure their engagement between superimposed belts of the offset 15 delivery conveyor; which traverses the path of travel of the offset delivery conveyor and the sealing machine conveyor without interference with or obstruction to the formers or followers of the latter; 20 which is timed so that all of the instrumentalities are operated continuously preferably from a common source of power; which may be installed with any of the well-known types of carton-making and sealing machines 25 without materially altering the construction of the latter; and which is simple in construction and efficient in operation.

This invention may receive a variety of mechanical expressions, some of which are 30 shown in the accompanying drawings, but it is to be expressly understood that these drawings are for purposes of illustration only and are not to be construed as defining the limits of the invention, reference being had to the appended claims for this purpose.

In said drawings:—

Fig. 1 is a side elevation showing a combination carton sealer equipped with delivery mechanism embodying the present invention;

Fig. 2 is a cross section on the line 2—2 of Fig. 1 showing the carton engaging clamps in position to receive a carton from a conveyor follower of the sealing machine;

Fig. 3 is a similar section showing the 45 carton engaging clamps in position to deposit the carton on the offset delivery conveyor;

Fig. 4 is a fragmentary top plan of the 50 combination sealer and delivery mechanism;

Fig. 5 is a perspective view of the carton transferring and delivery mechanism;

Fig. 6 is a transverse section through a 55 carton top-sealing machine showing another embodiment of the carton transferring and delivery mechanism.

In Figs. 1 to 5 of the drawings, the invention is shown installed in a combination carton making and sealing machine the supporting frame of which comprises side members 1, 1 connected by cross-pieces 2 to provide a rigid support for the operating parts of the entire assembly. Said frame is provided with legs 3 and the carton making, sealing, transferring and delivering devices are supported within this frame and operated by means and in the manner hereinafter described. Said machine is provided with carton flap-closing mechanism 4 preferably constructed and operating in the manner disclosed in Patent 1,096,918, and said flap closing mechanism is combined with the usual flap tucking and sealing devices (not shown) past which the cartons 5 are fed by means of a feed conveyor.

This feeding conveyor preferably comprises an endless carrier or chain 6 supported on and operated by suitable sprockets 7 and 8 mounted on driven shafts 9 and 10 journaled on the ends of the side members 1, 1, said sprockets being positioned on the 75 shafts in line with a centrally located conveyor way 11 extending longitudinally of the machine. The chain 6 is provided at suitable intervals with elongated plates 12, the tenoned ends 12' of which are guided in 80 suitable grooves 13 formed on the sides of way 11. Carton formers 14 and followers 15 are mounted on plates 12 in alternating relation, the formers 14 serving to carry empty cartons past the devices for sealing their bottom flaps, and the followers 15 serving to carry filled cartons past said devices to seal their top flaps. Suitable guides 16 are provided for preventing dislodgment of the 85 cartons from the formers and followers; said guides being supported on brackets 17 fixed to the conveyor way, the attaching means for said guides comprising bolts 18 providing for adjustment of guides 16 to accommodate cartons of different sizes.

The carton delivery mechanism of the present invention comprises two spaced superimposed endless belts, the top belt being indicated at 19 and the bottom belt at 20. Said belts are offset from the conveyor 105 6, and their receiving ends overlap the delivery end of conveyor 6 to provide for the transfer of filled cartons from followers 15 to said belts by devices hereinafter described. The receiving ends of said belts 110 are supported on pulleys 21 and 22 mounted

on driven shafts 23 and 24 suitably journaled on a stationary part of the machine. The lower belt 20 extends beyond belt 19 to provide in effect a moving platform onto which the cartons are deposited and moved between both belts which grip and carry the filled cartons to a final point of delivery (see Figs. 4 and 5). Suitable drier rollers 25, belt tighteners 26, 27, belt and roller supporting frames 28, 29, and a supporting pedestal 30 are indicated in Fig. 1, the operation and arrangement of these parts being well understood and not requiring a detailed explanation.

15 The carton transferring means comprises a plurality of independent relatively movable clamps reciprocable transversely of the paths of travel of the conveyor 6 and belt 20.

In the embodiment shown in Figs. 1 to 5, 20 two clamps 31 and 32 are employed. These clamps are disposed vertically for attachment at their upper ends to brackets 33 and 34 which respectively project from and form a part of relatively movable carriages 35 and 36 substantially C-shaped in cross-section (Fig. 5). These carriages are mounted on a track 37 attached at its ends to the side frames 1, 1, and extending transversely over conveyor 6 and belt 20, said carriages preferably being provided with anti-friction rollers 38 which engage the track and provide a rolling travel of the carriage. Since clamp 31 traverses the path of travel of conveyor 6, the said clamp is preferably of less width 30 than clamp 32 in order to provide sufficient clearance with respect to the moving formers and followers and to enable a maximum number of the same to be employed. Reference to Fig. 5 shows this difference in width 40 of the clamps and also a carton top-engaging stop 39 on the inner side of wide clamp 32 which stop prevents vertical displacement of the carton when engaged between the clamps and also acts as a guide when the carton is 45 being moved out of engagement therewith. Clamps 31 and 32 serve to engage the filled cartons on followers 15 and transport the same to the delivery conveyor, where the filled cartons are deposited on belt 20 and 50 conveyed away as above described.

In order to insure that the transferred cartons will be released from the clamps and engaged between belts 19 and 20, mechanism for this purpose is provided comprising 55 a plunger 40 positioned above belt 20 and reciprocable between clamps 31 and 32 in their carton delivery position (Fig. 4). Plunger 40 is mounted in any suitable manner and operated by any suitable mechanism. In 60 the form shown, the mounting for the plunger comprises stub shafts 41 and 42 positioned in the same horizontal plane and attached to the right-hand side member 1 by nuts 43. A lever 44 and a bell-crank 45 are 65 journaled on said stub-shafts, the upwardly

extending arms of which are equal in length. The upper ends of said lever and bell-crank are provided with bearing pins 46 on which bearings 47 projecting from one side of the plunger rod 48 are journaled.

The driving and operating mechanisms for the above described devices preferably comprise a source of power, as an electric motor 49, rigidly secured to the machine frame, preferably near the bottom thereof, the attaching means for said motor being of any suitable construction, here shown as a bracket 50 secured to the frame by bolts 51. The main drive shaft 52 is journaled in suitable bearings 53 on the top rails of side frames 1, 1 and carries at its far end a pulley 54 connected by a belt 55 to the driving pulley 56 of motor 49.

At the left hand side of the machine as shown in Figs. 2 and 3, shaft 52 is provided with a sprocket 57 alined with a sprocket 58 on shaft 10 and passing over said sprockets is a chain 59 which, by the means above described, drives shaft 10 and the conveyor chain 6. Driving power is transmitted to belts 19 and 20 by means of a chain 61 which passes around sprockets 62 and 63 on shaft 10 and stub shaft 24, and a chain 64 which passes around a second sprocket 65 on stub shaft 24 and a sprocket 66 on stub shaft 23.

The operating mechanism for the carton transporting carriages and clamps comprises a lever 67 pivotally mounted intermediate its ends on a bracket 68 secured to one end of the near side frame 1 (Fig. 5). Said lever carries at its lower end a roller 68' which engages in a cam groove 69 formed in a cam wheel 70 mounted on shaft 10, whereby a rocking movement is imparted to lever 67. An adjustable link 71 is connected at one end to the upper extremity of lever 67, the opposite end of said link being connected to one arm 72 of a bell-crank lever 73 vertically journaled in a suitable bearing 74 on the side frame 1 at the left of Fig. 5. The attaching devices for link 71 with lever 67 and arm 72 are preferably of the universal type, comprising in this instance a pair of pivotally connected yokes 77, 78 at each end of the link, the yokes of each pair being disposed at right angles to each other. An adjustable link 79 is pivotally connected at one end to the other arm 80 of bell-crank lever 73, by means of a yoke 81, the opposite end of link 79 being attached to carriage 35 by means of a yoke 81' pivotally connected to a yoke 82 projecting rearwardly from said carriage and preferably formed integral therewith.

Carriages 35 and 36 are interconnected 125 in such manner as to be reciprocated together along track 37 by the operating mechanism above described, while at the same time means are provided for intermittently imparting relative movement to said car-

riages in either direction, whereby the clamps 31 and 32 will be caused to grip and release the filled cartons at proper intervals during transportation of the cartons from conveyor 6 to belts 19 and 20. The interconnecting means for said carriages comprises a pair of links 83 and 84, disposed in a vertical plane, the lower ends of the links being pivotally connected to the upper part of carriages 35 and 36. Said links converge toward each other and their upper ends are pivotally connected by a pin of the usual type carrying a roller 85. Roller 85 engages in a cam guide or groove 86 formed in an upper standing bracket 87 bolted or otherwise rigidly secured to track 37, the cam guide and roller constituting the means for intermittently imparting relative movement to the carriages and clamps during their travel along track 37. For this purpose, cam groove or guide 86 (Fig. 3) is formed with a long, straight, high portion 86' and short, low portions 86'', 86''' curved upwardly and joining the ends of said high portion. The operating mechanism for plunger 40 comprises a cam wheel 88 mounted on shaft 10 and a roller 89 engaged in the cam groove 90 of said wheel and mounted on the lower arm 90' of bell-crank lever 45. The movement of conveyor 6, carriages 35, 36, belts 19 and 20, and plunger 40 are thus all derived from a common source of power, and the operating parts for each device are timed with relation to each other to actuate the same in the following manner:

The alternating formers and followers of conveyor 6 carry empty and filled cartons past the flap folding and sealing devices to the carton transferring mechanism comprised by carriages 35, 36 and clamps 31, 32. When a follower 15 carrying a filled carton reaches said mechanism, the clamps have been moved to the position shown in Fig. 2 and the filled carton passes between the same, the top of the carton being engaged under stop 39. In this position the clamps have received their maximum movement to the left, said movement of wide clamp 32 terminating a short distance to the right of follower 15 to provide clearance for the latter in its continued feeding movement. Clamp 31 begins to move to the right, displacing the filled carton laterally from the follower. During the movement of clamp 31 across the path of travel of follower 15, there will be sufficient clearance for the latter in its continued feeding movement, due to the relatively narrow width of said clamp. As the carton is being displaced from the follower the apex of links 83 and 84 is lifted by roller 85 and cam groove 86, and a relative movement of the carriages and clamps toward each other is produced which causes the clamps to grip the filled carton. The carriages, clamps and carton then continue

to move as a unit toward the delivery conveyor, until they reach approximately the delivery position (Fig. 3) where the cam groove and roller move the apex of links 83 and 84 downward, spreading the clamps and releasing the carton for deposit on belt 20. At this moment, plunger 40 is moved between the clamps to eject the carton therefrom and start it on its way to be gripped between belts 19 and 20, as above described. During transfer of the carton from follower 15 to belt 20 a former 14 carrying an empty carton will have passed by the path of travel of the carriages and clamps, and when the latter again move to the carton-receiving position (Fig. 2) another follower carrying a filled carton will have moved up to the clamps which then engage and transfer the carton as before.

It will thus be apparent that a continuously operating mechanism is provided for transferring filled and sealed cartons from followers alternating with formers on the feeding conveyor to an offset delivery conveyor, and that each filled carton is transferred when presented to the clamps by a movement of the latter to the offset delivery conveyor, whereby the formers carrying the bottom sealed empty cartons pass the transfer point without interruption and are returned to an operative who places the empty cartons on the followers after which they are filled, top-sealed and transferred to the offset delivery conveyor.

In the embodiment illustrated in Fig. 6, the invention is shown installed with a carton top-sealing machine, wherein the filled and sealed cartons are fed to carton transferring devices which transport the successive cartons from the feeding conveyor alternately to one or the other of a pair of offset delivery conveyors, one at each side of said feeding conveyor. The belts of the offset delivery conveyors are indicated at 91, 92, and 93, 94. The carton feeding conveyors of the top-sealing machine comprises the usual followers 95 carried on plates 96 which run in grooves on the usual conveyor way 97 and are attached at suitable intervals to a conveyor chain 98 which passes around a sprocket 99 secured to the driven shaft 100. The usual adjustable guide rails 101 are disposed at each side of the carton feeding conveyor for the purpose of preventing displacement of the cartons from the formers 95, said guide rails being slidably mounted in the usual manner on brackets 102 secured to the conveyor way 97.

Double acting carton transferring clamps are provided in the present embodiment; the narrow clamps being comprised by an elongated U-shaped bracket 103 depending from the bracket 104 of a centrally disposed carriage 105, the outer sides of said U-shaped bracket constituting the acting faces of the

clamp and providing, in effect, a single structure which takes the place of two clamps. The wide clamps 106 and 107 depend from the brackets 108, 109 of carriages 110 and 111, all of the aforementioned carriages being substantially C-shaped in cross-section and provided with anti-friction rollers 112 for engagement with a track 113 which extends transversely of the machine and is attached to the side frames 114.

The receiving ends of belts 91, 92 and 93, 94 are carried on pulleys 115, 116 and 117, 118. The pulleys 115 and 117 are mounted on driven shaft 119 which extends transversely of the machine, and pulleys 116 and 118 are mounted on stub shafts 120 and 121. Said shafts 119, 120 and 121 are journaled in suitable bearings on the side frames 114 and extend outside of the same, the extended ends of said shafts carrying the sprocket gears by which the shafts are driven.

To insure that the transferred cartons will be engaged between the upper and lower belts of the offset delivery conveyors, there is arranged adjacent each of these conveyors a pair of ejecting plungers 122, 123, one for each conveyor, said plungers operating in the same manner as set forth in connection with the first described embodiment of the invention.

The driving and operating mechanism for the above described instrumentalities comprises preferably an electric motor 124 mounted on a bracket 125 bolted or otherwise suitably secured to one side frame 114. The main drive shaft 126 is journaled in suitable bearings on the top rails of said side frames and carries at one end a large pulley 127 over which passes one end of a driving belt 128, the opposite end of said belt passing around the driving pulley 129 of the motor. Shaft 100 is driven from shaft 126 by the following means:—at the left of the machine, the extended end of shaft 100 carries a sprocket gear 130 over which passes a chain 131, the said chain also passing over a sprocket 132 carried by the extended left end of shaft 126. Shaft 100 also carries at one end a sprocket 133 alined with a sprocket 134 of shaft 121, the latter shaft being driven by a chain 135 which passes around sprockets 133 and 134. At the right side of the machine the extended end of shaft 100 carries a sprocket 136 alined with a sprocket 137 mounted on the extended end of shaft 120, the latter shaft being driven by an endless chain 138 which passes around sprockets 136 and 137. Shaft 120 also carries a sprocket 139 alined with a sprocket 140 mounted on the extended end of shaft 119, the latter shaft being driven by an endless chain 141 which passes around sprockets 139 and 140.

The operating mechanism for the carton transporting carriages and clamps com-

prises a lever 142 pivotally mounted intermediate its ends on the bracket 143 secured to the left side frame 114. Said lever carries at its lower end a roller 144 which engages in a cam groove 145 formed in a cam wheel 146 mounted on shaft 100 whereby on rotation of the latter the cam groove and roller impart a rocking movement to lever 142. The upper end of lever 142 is connected to one arm of a bell-crank lever 147 in a manner and by means similar to that set forth in the first described embodiment of the invention. The other arm of bell-crank lever 147 is connected by a link 148 to the central carriage 105, said carriage being connected with carriages 110 and 111 by toggle levers 149 and 150.

Carriages 105, 110 and 111 are interconnected in such manner as to be reciprocated together along track 113 by the operating mechanism just described, while at the same time means are provided for imparting relative movement to said carriages in either direction whereby the clamps 103 and 106 or 103 and 107 will be caused to grip and release the filled cartons at the proper time during transportation of the same from the carton feeding conveyor to either of the offset delivery conveyors. The link connections 149 and 150 carry at their apices rollers 151 and 152 which engage respectively in cam grooves 153 and 154 formed on up-standing ribbed brackets 155 and 156 bolted or otherwise suitably secured to the track 113. Cam grooves 153 and 154 (Fig. 6) are formed with long, straight, high portions 153', 154' and short, low portions 153'', 154'' curved upwardly and joining the ends of said high portions respectively.

The gripping, transporting and releasing movements of the clamps are substantially the same as set forth in connection with the first described embodiment of this invention except that the three clamps traverse the path of travel of the three conveyors and transfer successive cartons on the feeding conveyor alternately, to the delivery conveyors at both sides of said feeding conveyor. Each transferred carton is gripped between one narrow face of the U-shaped clamp 103 and either of the wide clamps 106 or 107 in accordance with the direction of movement of the entire carton transferring mechanism. By this construction, the filling, sealing and delivery of cartons with great rapidity is facilitated, since a greater number of carton followers may be employed on the carton feeding conveyor, and the delivery of the sealed and filled cartons will be expedited by transferring the successive cartons on the feeding conveyor alternately to one and then the other of the delivery conveyors.

The operating mechanism for the ejecting plungers 122 and 123 comprises bell-

crank levers 157 and 158 mounted on stub shafts 159 and 160 suitably secured to the side frames 114. Upwardly extending arms 161 and 162 of said bell-cranks are attached 5 to the plungers 122 and 123. The short arms 163 and 164 of said bell-cranks are provided at their ends with rollers 165 and 166 which engage in suitable cam grooves (not shown) of cam wheels 167 and 168 secured 10 on driven shaft 100.

All of the various instrumentalities of this last described embodiment of the invention are timed in a suitable manner to produce a continuous operation of the machine, the double acting clamps transferring the successive cartons on the carton feeding conveyor alternately to the delivery conveyors at each side of the feeding conveyor and the ejecting plungers operating at 15 the proper moment to eject the released cartons from their clamps and insure engagement of the cartons between the upper and lower belts of the respective offset delivery conveyors.

25 What is claimed is:—

1. In combination, a pair of spaced conveyors, a pair of clamps for transferring cartons from one to the other of said conveyors, a stationary cam guide, and operating means for said clamps cooperating with said cam guide whereby the clamps are caused to successively engage a carton on one conveyor, transport the carton laterally from said conveyor, and release the transported carton on arrival of the same at the other conveyor.

2. In combination, a pair of spaced conveyors, a pair of clamps for transporting cartons from one conveyor to the other conveyor, a stationary cam guide, operating means for said clamps cooperating with said cam guide whereby the clamps are caused to grip a carton on one conveyor, transport the carton laterally from said conveyor, and release the transported carton upon arrival of the same at the other conveyor, and means for ejecting the carton from said clamps after release thereby.

3. In combination, a carton feeding conveyor, delivery means at one side of said conveyor, a plurality of clamps for transferring cartons from said feeding conveyor to the delivery means, operating mechanism for said clamps causing the same to engage a carton on the feeding conveyor and transport the same to the delivery means, and a device offset from the feeding conveyor for ejecting the transported carton from said clamps.

60 4. In combination, a carton feeding conveyor, a delivery conveyor at one side of said conveyor, a pair of reciprocating feeding conveyor, a pair of reciprocating clamps for transferring cartons from the feeding conveyor to said delivery conveyor, operating mechanism for said clamps caus-

ing the same to engage a carton on the feeding conveyor and release the carton after it has been transported to the delivery conveyor, and a pusher offset from the feeding conveyor for ejecting the transported carton 70 from the clamps onto the delivery conveyor.

5. In combination, a pair of spaced parallel conveyors, a pair of relatively movable clamps for transferring cartons from one to the other of said conveyors, driving mechanism 75 for reciprocating said clamps across the path of travel of said conveyors, a stationary cam guide, and means connecting said driving mechanism with said clamps, said means cooperating with the cam guide 80 to engage the clamps with a carton on one conveyor and release the clamps upon arrival of the carton at the other conveyor.

6. In combination, two parallel conveyors, a track extending transversely over said conveyors, a plurality of carriages reciprocable along said track, driving means for said conveyors and carriages, clamps depending from said carriages for movement 85 across the path of travel of said conveyors, and means for imparting relative movement of said carriages and clamps at predetermined intervals in their reciprocatory movement, said means comprising a stationary cam guide and connections between the carriages and said driving means cooperating 90 with the cam guide.

7. In combination, a carton feeding conveyor and a delivery conveyor arranged in parallel spaced relation, means for transferring cartons from the feeding conveyor to the delivery conveyor, said transferring means comprising a plurality of independent clamps reciprocable across the path of travel of the conveyors, means causing said clamps to successively engage, transport and release a carton during transfer of the same from the feeding conveyor to the delivery conveyor, and means offset from the feeding conveyor for ejecting the released carton 100 from said clamps.

8. In combination, two parallel conveyors disposed in overlapping end relation, a track extending transversely above the overlapped ends of said conveyors, and means for transferring articles from one conveyor to the other conveyor, said means comprising independent clamps reciprocable along said track, operating means for said clamps, a stationary cam guide, and connections between said operating means and clamps cooperating with said cam guide.

9. In combination, a pair of spaced conveyors, reciprocating devices for transferring cartons from one to the other of said conveyors, mechanism for reciprocating said devices, and means intermittently imparting carton gripping and releasing movements to said devices during their reciprocating 125 movement.

10. In combination, a pair of spaced conveyors, a plurality of reciprocating clamps for transferring cartons from one to the other of said conveyors, mechanism for reciprocating said clamps, and means for intermittently moving the clamps toward and away from each other during their reciprocating movement.
11. In combination, a carton feeding conveyor, delivery mechanism at one side of said feeding conveyor, reciprocating devices for transporting cartons from the feeding conveyor to said delivery mechanism, means for reciprocating said devices, means for intermittently imparting carton gripping and releasing movements to the transporting devices during their reciprocating movement, and means at the delivery conveyor for ejecting the transported cartons from said devices.
12. In combination, a pair of spaced parallel conveyors, a track extending above the conveyors transversely of the same, a plurality of relatively movable carriages mounted on said track and provided with clamps for transferring cartons from one to the other of said conveyors, mechanism for reciprocating said carriages along the track, and means for intermittently moving the carriages toward and away from each other during their reciprocating movement.
13. In combination, a carton feeding conveyor, a pair of delivery conveyors one at each side of said feeding conveyor, reciprocating devices for transferring successive cartons on the feeding conveyor alternately to the delivery conveyors, mechanism for reciprocating said devices, and means for intermittently imparting carton gripping and releasing movements to said devices during their reciprocating movement.
14. In combination, a carton feeding conveyor, a pair of carton delivery conveyors one at each side of said feeding conveyor, a plurality of clamps for alternately transferring successive cartons on the feeding conveyor to the delivery conveyors at each side of said feeding conveyor, a plurality of stationary cam guides, and operating means for said clamps cooperating with said cam guides.
15. In combination, a carton feeding conveyor, two offset delivery conveyors one at each side of said feeding conveyor, a plurality of carriages reciprocable across the path of travel of said conveyors, clamps on said carriages for transferring cartons from the feeding conveyor to the delivery conveyors, stationary cam guides, operative connections between said carriages and said cam guides, and means for reciprocating said carriages.
16. In combination, a carton feeding conveyor, two delivery conveyors one at each side of said feeding conveyor, a track extending transversely above said conveyors,
- a plurality of carriages reciprocable along said track and provided with depending clamps for transferring cartons from the feeding conveyor to the delivery conveyors, operating means for said carriages, and means for imparting carton engaging and releasing movements to said clamps during reciprocation of their carriages, said means comprising stationary cam guides, toggle levers connecting said carriages and rollers on said levers cooperating with said cam guides.
17. In combination, a carton feeding conveyor, a pair of delivery conveyors one at each side of said feeding conveyor, a plurality of movable clamps for transferring successive cartons on the feeding conveyor alternately to the delivery conveyors, and a pair of devices offset from the carton feeding conveyor for ejecting the cartons from said clamps onto said delivery conveyors.
18. In combination, a carton feeding conveyor, a pair of delivery conveyors one at each side of said feeding conveyor and arranged in spaced relation therewith, clamps reciprocable across the path of travel of said conveyors for transferring successive cartons on the feeding conveyor alternately to the delivery conveyors, and a pair of reciprocating plungers one at each delivery conveyor for ejecting the transported cartons from said clamps.
19. In combination, a carton feeding conveyor, a pair of offset delivery conveyors one at each side of said carton feeding conveyor, a track extending above said conveyors transversely of the same, a central carriage and a pair of side carriages mounted on said track, clamps depending from the carriages, means for reciprocating the carriages along the track, and means intermittently imparting relative movement to said carriages during their reciprocating movement.
20. In combination, a carton feeding conveyor, a pair of delivery conveyors one at each side of said carton feeding conveyor, reciprocating means for transferring cartons on the feeding conveyor to the delivery conveyors, said means comprising a central carton engaging device and a pair of carton engaging devices one at each side of said central device, mechanism for reciprocating the carton engaging devices, and means for intermittently imparting relative movement to the carton engaging devices during their reciprocating movement whereby said devices are caused to grip and release the cartons at predetermined intervals.
21. In combination, a carton feeding conveyor, a pair of delivery conveyors one at each side of said carton feeding conveyor, reciprocating devices for transferring cartons from the feeding conveyor to the delivery conveyors, said devices comprising a

central carriage, a pair of carriages one at each side of said central carriage, and clamps depending from the central and side carriages, mechanism for reciprocating said carriages and clamps, and means for intermittently imparting relative movement to the carriages during their reciprocating movement whereby said clamps are caused to grip and release the cartons at predetermined intervals.

22. In combination, a carton feeding conveyor, a pair of delivery conveyors one at each side of said carton feeding conveyor, reciprocating means for transferring cartons from the feeding conveyor to the delivery conveyors, said means comprising a narrow clamp and a wide clamp at each side of said narrow clamp, mechanism for reciprocating said clamps, and means for intermittently moving the wide clamps toward and away from the narrow clamp during reciprocating movement of said clamps whereby the latter are caused to grip and release the cartons at predetermined intervals.

23. In combination, a carton feeding conveyor, a pair of offset delivery conveyors one at each side of said carton feeding conveyor, a track extending transversely of said conveyors, and means for transferring successive cartons on the feeding conveyor alternately to the delivering conveyors, said means comprising a central carriage and a pair of side carriages slidably mounted on said track and provided with track-engaging rollers.

24. Carton transporting means comprising a track, a plurality of carriages slidably mounted on said track, means for reciprocating said carriages, cam guide means, and connections between said carriages cooperating with said cam guide means whereby a relative movement is imparted to the carriages during their reciprocation.

25. Carton transporting means comprising a track, three carriages on said track, means for reciprocating said carriages, cam guides, and connections between said carriages cooperating with said cam guides whereby the outer carriages are moved toward and away from the central carriage during reciprocation of the carriages.

26. In combination, a conveyor provided with spaced carton carrying elements, an

offset delivery mechanism, devices movable to and from the conveyor and said delivery mechanism, and operating means for said devices causing the same to transfer cartons on alternate carrying elements of the conveyor to said delivery mechanism.

27. In combination, a carton feeding conveyor provided with spaced carton carrying elements, a delivery conveyor arranged in spaced parallel relation with respect to said feeding conveyor, clamps reciprocable across the paths of travel of said conveyors, and operating means for said clamps causing the same to transfer cartons on alternate carrying elements of said feeding conveyor to the delivery conveyor.

28. In combination, a conveyor provided with spaced carton carrying elements, a delivery mechanism at one side of said conveyor, devices movable to and from the conveyor and said delivery mechanism, operating means for said devices causing the same to transport cartons on alternate carrying elements of said conveyor to the delivery mechanism, and means for ejecting the transported cartons from said devices.

29. In combination, a conveyor provided with spaced carton carrying elements, an offset delivery mechanism, a pair of reciprocating carton transferring devices, operating mechanism for said devices causing the same to transport cartons on alternate carrying elements of said conveyor to the delivery mechanism, and means imparting carton gripping and releasing movements to the transferring devices during their reciprocating movement.

30. In combination, a carton feeding conveyor provided with spaced carton carrying elements, a delivery conveyor arranged in parallel spaced relation with respect to said feeding conveyor, a pair of reciprocating clamps, operating mechanism for said clamps causing the same to transport cartons on alternate carrying elements of the feeding conveyor to said delivery conveyor, and means intermittently imparting carton engaging and releasing movements to said clamps during their reciprocating movement.

In testimony whereof I have signed this specification.

GEORGE H. BENT.
